UNITED STATES PATENT OFFICE.

JOHN W. KAUFMANN, OF BALTIMORE, MARYLAND.

REPRODUCER FOR TALKING-MACHINES.

1,381,998.

Specification of Letters Patent. Patented June 21, 1921.

Application filed June 9, 1920. Serial No. 387,640.

To all whom it may concern:

Be it known that I, JOHN W. KAUFMANN, a citizen of the United States, and a resident of Baltimore, in the State of Maryland, have 5 invented certain new and useful Improvements in Reproducers for Talking-Machines, of which the following is a specification.

My invention is an improvement in reproducers for talking machines, and has for 10 its object to provide a new and improved connection between the needle and the diaphragm controlling lever for transmitting in as perfect a manner as possible the movement of the needle to the diaphragm, to provide for a softening of the tone and elimination 15 of mechanical elements therefrom, as well as for increasing the volume of tone.

In the drawings:

Figure 1 is a perspective view of the improved reproducer;

Fig. 2 is a front view;

Fig. 3 is a section on the line 3—3 of Fig. 2.

In the embodiment of the invention 25 shown, the case 1 of the reproducer box has the usual central nipple 2, for receiving the inlet end of the amplifier 3. The diaphragm 4 is of any usual or desired construction, being held in place in the case by means of 30 gaskets 5, the said gaskets being formed from rubber or the like, preferably tubing, as shown. A ring 6 is secured to the case to hold the gaskets and the diaphragm in place and the reproducing lever 7 is connected 35 with the center of the diaphragm in the usual manner.

The case 1 of the reproducer box has a radial extension at one side, indicated at 8, the said extension in the present instance 40 having two bearings 9, through which are threaded set screws 10. The inner ends of these set screws are pointed, as shown, and the set screws are held in adjusted position by lock nuts 11. The lever has a cross head 12 at its outer end, and an angular extension 13 at the cross head, the said extension 13 extending at approximately right angles to the lever. This cross head 12 has conical 45 openings in its ends, which are engaged by the set screws 10 before mentioned, to pivotally mount the reproducer lever on the radial extension.

A needle holder 14 is mounted at the op-

posite side of the box from the radial extension. This needle holder 14 has the usual 55 axial opening for receiving the needle, and the set screw 15 for holding the needle in place, and at the opposite end from the axial opening the needle holder has a cross head 16 and an angular extension 17 extending at approximately a right angle to the needle holder.

A segmental plate 18 is secured to the ring 6 at a point diametrically opposite the radial extension by means of screws or the like, and this plate is recessed at its center on an arc which has the center of the diaphragm for its center. The plate 18 carries a pair of alined bearings 19, through which are threaded set screws 20 similar to 70 the screws 10 before mentioned. The inner ends of these screws are tapering or pointed, as shown, and they are adapted to engage similarly shaped openings in the ends of the cross head. 75

Each screw has a lock nut 21 at the outer face of the bearing for holding the screw in adjusted position. Thus both the reproducing lever and the needle holder are pivotally connected to the sound box. The resilient 80 connection between the reproducing lever and the needle holder is provided by an arc shaped spring 22. This spring has its ends connected with the extensions 13 and 17, and it will be noticed, referring to Fig. 3, that 85 these extensions extend well up on to the arms of the spring, thus providing rigidity at the ends of the spring.

The plate 18 and the mounting of the needle holder thereon provides a species of 90 counter-weight, which steadies the movement of the reproducer box under the impulse of the needle. The improved method of mounting the reproducer not only provides a soft tone, eliminating disagreeable 95 scraping, squeaking and mechanical elements, but also provides for increased volume of tone. The movement of the needle is amplified at the diaphragm by the connection between the needle holder and the 100 reproducer lever.

It will be noticed, referring to Fig. 3, that while the length of the extension 13 is about half the length of the reproducing lever 7, the extension 17 is only about one-third the length of the needle holder 14, that

is, the extension 13 is relatively long as compared with the extension 17. This arrangement increases the leverage between the needle point and the connection of the lever 7 with the diaphragm. A greater leverage is exerted on the spring 22 at the needle holder end, and the spring, because of the length of the extension 13, exerts a greater leverage on the reproducer lever. The leverage is thus increased at the point 17 and at the point 13. It will be noticed, referring to Fig. 3, that the ring 6 is only a partial ring, the ends of the ring being received beneath the edge of the segmental plate 18. The ring, however, does not extend entirely around beneath the plate.

The extensions 13 and 17 do not touch the spring throughout their length but only at the point where the screws pass through the spring. Here it will be noticed that each extension has enlargements somewhat in the form of washers, which space the spring from the body of the extension.

I claim:

1. In reproducers, the combination with the sound box, the reproducing lever and the needle holder, of pivotal mountings at the inner end of the needle holder and at the outer end of the reproducing lever for said needle holder and reproducing lever, the sound box having a radial extension which carries the pivotal connection of the reproducing lever, and a segmental plate secured to the box at the opposite side from the extension and extending over the diaphragm to near the center thereof and carrying the pivotal mounting of the needle holder, and a resilient connection between said needle holder and reproducing lever at the pivotal connection, said connection comprising a plate spring, one end of which is rigid with the lever and the other with the needle holder, said spring being arched longitudinally, and the needle holder and the reproducing lever having angular extensions lying upon the spring at the ends thereof and rigidly secured thereto.

2. In reproducers, the combination with the sound box, the reproducing lever and the needle holder, of pivotal mountings at the inner end of the needle holder and at the outer end of the reproducing lever for said needle holder and reproducing lever, the sound box having a radial extension which carries the pivotal connection of the reproducing lever, and a segmental plate secured to the box at the opposite side from the extension and extending over the diaphragm to near the center thereof and carrying the pivotal mounting of the needle holder, and a resilient connection between said needle holder and reproducing lever at the pivotal connection, said connection comprising a plate spring, one end of which is rigid with the lever and the other with the needle holder,

3. In reproducers, the combination with the sound box, the reproducing lever and the needle holder, of pivotal mountings at the inner end of the needle holder and at the outer end of the reproducing lever pivotally supporting said needle holder and reproducing lever at points equally spaced beyond one face of the sound box, the sound box having a radial extension which carries the pivotal connection of the reproducing lever, and a segmental plate secured to the box at the opposite side from the extension and extending over the diaphragm to near the center thereof and carrying the pivotal mounting of the needle holder, and a resilient connection in normal condition between said needle holder and reproducing lever at the pivotal mountings.

4. In a reproducer, a sound box, a reproducing lever, a needle holder, self supporting pivots for the said lever and said needle holder on the sound box, and a bow shaped spring in normal condition connected at opposite ends to said lever and said holder.

5. In reproducers, the combination with the sound box, the reproducing lever and the needle holder, of pivotal mountings at the inner end of the needle holder and at the outer end of the reproducing lever for said needle holder and reproducing lever, and a segmental plate secured to the box at the opposite side from the extension and extending over the diaphragm to near the center thereof and carrying the pivotal mounting of the needle holder, and a resilient connection in normal condition between said needle holder and reproducing lever secured at its ends thereto.

6. In reproducers, the combination with the sound box, the reproducing lever and the needle holder, of pivotal mountings at the inner end of the needle holder and at the outer end of the reproducing lever for said needle holder and reproducing lever each including spaced bearings, and a resilient connection between said needle holder and reproducing lever, secured to the latter between the bearings.

7. In reproducers, the combination with the sound box, the reproducing lever and the needle holder, of pivotal mountings at the inner end of the needle holder and at the outer end of the reproducing lever for said needle holder and reproducing lever, the sound box having a radial extension which carries the pivotal connection of the reproducing lever, and a segmental plate secured to the box at the opposite side from the extension and extending over the diaphragm to near the center thereof and carrying the pivotal mounting of the needle holder, and a resilient connection in normal condition between said needle holder and reproducing lever.

8. In reproducers, the combination with

the sound box, the reproducing lever and the needle holder, of pivotal mountings at the inner end of the needle holder and at the outer end of the reproducing lever for said 5 needle holder and reproducing lever, a spring in normal condition connecting the needle holder and the reproducing lever,

both the needle holder and the reproducing lever having angular extensions for connection with the spring, and the extension of 10 the reproducer lever being relatively greater than the extension of the needle holder.

JOHN W. KAUFMANN.
